Primary Examiner — Patricia A Palasik(74) *Attorney, Agent, or Firm* — Bradford B. Wright(57) **CLAIM**

The ornamental design for a coated abrasive disc, as shown and described.

DESCRIPTION

FIG. 1 is a perspective view of a coated abrasive disc showing the new design for a coated abrasive disc. As shown, the coated abrasive disc is oriented with the top surface shown uppermost on the disc;

FIG. 2 is an enlarged view of region 2 in FIG. 1;

FIG. 3 is a top view of the coated abrasive disc;

FIG. 4 is a left side view of the coated abrasive disc;

FIG. 5 is a right side view of the coated abrasive disc;

FIG. 6 is a front side view of the coated abrasive disc; and,

FIG. 7 is a back side view of the coated abrasive disc.

The broken lines in the drawings depict portions of the coated abrasive disc which form no part of the claimed design.
